UNITED STATES PATENT OFFICE.

ALBERT B. SIMON, OF SAN FRANCISCO, CALIFORNIA.

FABRIC-FRAME.

1,345,030.

Specification of Letters Patent. Patented June 29, 1920.

Application filed March 10, 1920. Serial No. 364,698.

To all whom it may concern:

Be it known that I, ALBERT B. SIMON, a citizen of the United States, and a resident of the city and county of San Francisco,

5 State of California, have invented new and useful Improvements in Fabric-Frames, of which the following is a specification.

My invention has for its object means whereby fabric may be stretched and dried 10 and is particularly adapted to the stretching and drying of lace curtains, and the like.

By referring to the accompanying drawings my invention will be made clear.

Figure 1 is a back view of my frame and 15 its operating mechanism.

Fig. 2 is a detail of the operating mechanism with a portion of the cover plate removed to better disclose the moving parts.

Fig. 3 is a cross section of Fig. 2 through 20 the center with certain of the parts shown in view.

Fig. 4 is a detail of the manner of forming the ends of the lateral members to insure their sliding engagement.

25 Fig. 5 is a fragmentary sectional view of the connection between an end member and one of the moving parts.

Throughout the figures the same numerals refer to identical parts.

30 The sides of the frame are indicated by the numerals 1, 2, 3, 4, to which I prefer to attach a plurality of clamps as 5, 6, 7, 8, suitably spaced, and which are used to clamp the edges of the fabric as at 9, 10; a portion only

35 of the fabric being shown in the illustration. The sides 1, 2, 3, 4 are supported respectively from central members 11, 12, 13, 14 on which are mounted the racks 15, 16, 17, 18 respectively, and which racks are in mesh with the

40 pinion 19. This pinion is fixed to the shaft 20 such that the rotation of the said pinion causes the simultaneous operation of the racks either to expand or contract the frame sides 1, 2, 3, 4.

45 The shaft 20 is mounted within the two plates 21, 22 which I prefer to form with the corner members as 23, 24. These corner members also serve to retain the spaced relation between the plates 21, 22, and also 50 serve as guides against which the racks operate on their faces opposite to the tooth side.

The shaft 20 is operable by the crank 25, which I prefer to drill and provide with a 55 pin 26, which may be used to engage any of the holes in the plate 21 as at 27, or a ratchet

and pawl, or any other holding means, whereby the arm or crank 25 may be fixed in any desired position, may be employed.

Referring to Fig. 4, which shows one of 60 the corners of the frame, the frame side members 3 and 4, are in loose slideable engagement and it will be noted that one of these sides 3 is slotted at 28 and adapted to loosely engage the tongue 29 of the side 4, so 65 that all of the sides may be moved with respect to each other and will be retained at all times within the same plane.

The operation is as follows:

The lever 25 is rotated in a contra-clockwise direction thereby drawing all the members of the frame inward or toward each other. The clamps as 5, 6, 7, 8 are now affixed to the fabric all around its periphery. The crank 25 is now to be rotated in the 75 clockwise direction until the fabric is stretched to the desired degree when the pin 26 is to be inserted in one of the holes as 27 thus locking the frame in its expanded position and with the fabric stretched. When 80 the desired stretching or drying is completed the pin is removed when the frame members are loosened by the contra-clockwise revolution of the pinion when the fabric may be removed from the clips or clamps. 85

Attention is directed to the means that are provided whereby the frame may readily be adapted to support itself and which consists of the feet 30, 31 and the back member 32 screwed into member 4 whereby the frame 90 may be stood up like an easel with the member 1 on the bottom and the member 4 on the top. The feet and back member may, however, be located on any of the other sides with equal facility.

95 The manner of joining the sides to the rack operated members and to the back member is preferably that of a screw thread on the member and a corresponding screw threaded socket in the side, as shown in the 100 detail, Fig. 5.

Where wet fabric is to be stretched it is advisable to use wood throughout the entire structure to prevent staining of the fabric, and I prefer to make all the parts, including 105 the racks, members and sides, and the screw threads by which they are engaged, of wood throughout, but I do not wish to limit myself to any specific material.

I claim:

110 1. In a frame for stretching and drying fabric and the like, a plurality of members

- arranged polygonally and movable relatively at right angles to their length, a rack for each member arranged at right angles thereto, a pinion to operate the racks and means supporting the racks about the pinion, substantially as and for the purpose set forth.
2. In a frame for stretching and drying fabric and the like, a plurality of members arranged polygonally and movable relatively at right angles to their length, a rack for each member arranged at right angles thereto, a pinion to operate the racks and means supporting the racks about the pinion, and means for rotating the pinion to expand or contract the frame, and locking means therefor.
3. In a frame for drying fabric and the like, a quadrangular frame whose sides are

relatively movable, a rack at right angles to each side and centrally affixed thereto, a pinion substantially centrally disposed and engaging all the racks, and means for rotating the pinion whereby the sides are moved.

4. In a frame for drying fabric and the like, a quadrangular frame whose sides are relatively movable, a rack at right angles to each side and centrally affixed thereto, a pinion substantially centrally disposed and engaging all the racks, and means for rotating the pinion whereby the sides are moved, and means on the sides for securing the edges of the fabric and locking means holding the slides apart.

In testimony whereof I have hereunto set my hand.

ALBERT B. SIMON.
